UNITED STATES PATENT OFFICE.

JOHN D. CURTIS, OF WORCESTER, MASSACHUSETTS.

SPOOL FOR WINDING BARBED FENCING.

SPECIFICATION forming part of Letters Patent No. 255,147, dated March 21, 1882.

Application filed December 27, 1881. (No model.)

To all whom it may concern:

Be it known that I, JOHN D. CURTIS, of Worcester, in the county of Worcester and State of Massachusetts, have invented certain new and useful Improvements in Spools for Winding Flat-Strip Barbed Fencing; and I declare the following to be a description of my said invention sufficiently full, clear, and exact to enable others skilled in the art to which it appertains to make and use the same, reference being had to the accompanying drawings, which form a part of this specification.

The object of my present invention is to provide a spool or device for winding flat-strip barbed fencing which will insure the convenient and regular winding and unwinding of the strip without liability of tangling or interlocking the barbs, said spool being more especially for use in connection with galvanizing apparatus, or for receiving the strip from the barbing-machines and delivering it to the galvanizing apparatus after the barbs have been attached thereto, it being quite desirable that the delivery of the strip should proceed at a uniform tension, and without the snapping or shaking effect which occurs when the barbs become caught and are then suddenly released, and also to avoid loosening the barbs or slipping them upon the strip or ribbon-wire before they become permanently fixed by means of the galvanizing metal. Another object is to make a spool which, while being of comparatively small diameter, shall contain a large quantity of the fence material. These objects I attain by a spool device constructed as herein shown and described.

In the drawings, Figure 1 is a side view of my improved spool for flat-strip barbed fencing. Fig. 2 is a transverse section at line *ww*, Fig. 1; and Fig. 3 is a longitudinal section at line *xx*, Fig. 2.

My improved spool consists of a central cylinder or barrel, *A*, two end disks or heads, *B*, and a greater or less number of intermediate flanges or disks, *C*, combined in such manner as to form a series of grooves or spaces of the proper width to receive and support the fence-strip or metal ribbon *D*, with its barbs *d*, in a single volute or roll, while the said intermediate disks are provided with inclines, guides, or passways *E* for transferring the

strip from the outer part of one groove to the inner part of the groove adjacent thereto without injuring the fence-strip or interfering with the wound portions, so that the entire spool can be filled by a continuous strip or ribbon, and the same or any portion thereof unwound and rewound with convenience and facility, and without the barbs catching or locking onto the adjacent coils or against each other. The end disks or heads, *B*, are made full circles, while the intermediate disks or flanges, *C*, have a slit or opening at one side, which forms the passway *E*. The bottom *e* of the passway is made with a flat surface for supporting the fence-strip *D*, said flat surface commencing with a rounded corner, *f*, at the periphery of the disk *C*, and extending inward to meet the barrel *A* tangent, or nearly so, with its surface, so that the fence-strip will not receive a sharp bend when carried from one groove to the next. The upper part of the passway has a side inclination, the disk being beveled off somewhat in the form of the inclination of a screw-thread, as shown at *m*, so that the fence-strip can pass across from one groove to the next at an easy inclination.

In the present instance a spool with four grooves, *F'* *F''* *F³* *F⁴*, or winding-spaces is shown; but, if desired, any number of grooves may be used, whether more or less than herein illustrated. The spool may be made entirely of metal, or it may be formed of wood, with the sides of the disks *B* and flanges *C* lined with sheet metal. The barbed fencing-strip is wound upon the spool until the first groove, *F'*, is filled. It is then carried, by shifting the position of the spool laterally or otherwise, across the passway *F* into the second groove, *F''*, as indicated, which groove is then filled, and so on through the entire series of grooves. The spool, being of comparatively small diameter in proportion to the quantity of material which it can contain, does not give excessive strain on the operating mechanism when winding near the periphery, as would occur with a spool having only a single groove and of sufficient diameter to contain an equal quantity of the barbed fencing-strip.

If desired, the fencing-strips could be put up for the market on this style of spool; but the chief utility of my invention is for winding and rewinding the barbed strips during

the various processes incident to the manufacture of this class of fence material.

What I claim as of my invention, and desire to secure by Letters Patent, is—

- 5 1. A spool for winding flat-barbed fencing material, constructed with a series of grooves or spaces with intervening flanges or separating disks, provided with inclines, guides, or passways for facilitating the transfer of the
- 10 fence-strand from one groove or space to the next, as hereinbefore set forth.

2. The combination, with the barrel A and head-disks B, of the intermediate disks or flanges, C, having passways E, with flat supporting-surfaces *e* and inclines *m*, substantially 15 as and for the purpose set forth.

Witness my hand this 21st day of December, A. D. 1881.

JOHN D. CURTIS.
